SOUND RECORDING

John H. McLeod and Richard S. Morse, Rochester,
N. Y., assignors to Eastman Kodak Company,
Rochester, N. Y., a corporation of New Jersey

Application October 13, 1937, Serial No. 168,777

10 Claims. (Cl. 179—100.3)

This invention relates to sound recording and particularly to push-pull sound-on-film recording wherein the sound record is divided or doubly recorded on two tracks which are usually immediately adjacent to each other on the film and in which the variations in light transmission are 180 degrees out of phase.

Although it is confined to push-pull recording, the invention may be applied either to variable 10 density or variable width systems. It is a primary object of the invention to provide a sound recording system which will permit variable density to be used with class B push-pull recording.

15 The term "Class B Push-Pull" is used by those skilled in this art to refer to systems in which each half of the positive double sound track comprises a variable width which follows one half of each cycle of the signal being recorded, but 20 which remains small and constant during the other half of each cycle. An example of such a track appears as Fig. 2 of the accompanying drawings. It will be noted that the two halves of the track are 180 degrees out of phase and 25 hence when the width of one track is varying, that of the other is small and constant. As is well known, Class B recordings have usually been produced by using a mask having two triangular openings—one inverted, the other upright with 30 their vertices on the same horizontal line. This gives a double triangular slot which when reflected from a galvanometer through a narrow slit forms a double light beam of this Class B push-pull type. Such systems need not be discussed in detail here especially since galvanometers do not lend themselves to variable density 35 recordings as readily as do ribbon valve systems and flashing lamp systems. Class A systems are those in which each of the two sound tracks represent a full wave including both halves of each cycle.

It is an object of the invention to provide Class B push-pull sound tracks having variable density rather than variable width and further 45 to provide apparatus using only electrical means for producing this Class B effect.

It is a particular object of the invention to produce such a sound record using flashing lamps.

The advantages of Class B recordings are well 50 known. For example, such a recording is automatically "noiseless" in the sense in which this word is commonly employed in this art, since the light transmission of the positive sound track tends toward zero for low signal intensities (low 55 sound volume). In Class A systems or non push-

pull systems, so-called "noiseless" recording may be obtained by biasing the valve or a cooperating mask according to the total sound volume. In such systems there is an inherent time delay so that the biasing action will not affect the individual cycles. This permits a swishing noise when changing from a loud to a soft note or to a region of silence, during the brief interval before the noiseless feature takes effect. This swishing effect is particularly noticeable with piano recordings wherein each note is momentarily loud. Class B recordings overcome all these difficulties since the noiseless feature is automatic and the sound track width or density is determined solely by the particular cycle being recorded. Thus another of the advantages of the present invention is the combination of the well known advantages of variable density recordings with the advantages of Class B push-pull recording.

According to the invention, a half-wave rectifier is placed in series with each of the two light modulating devices which may be of the ribbon type, flashing lamp type, etc., or even of the galvanometer type although in the latter case there is little advantage gained over an optical mask such as those now in use.

It is an object of one special embodiment of the invention to combine push-pull amplification with push-pull recording and to use the electron discharge devices of the amplifier as the rectifiers to give "Class B Recordings". Thus all the advantages of push-pull amplification and of our broad invention are combined in a simple, convenient and new manner.

It is an object of another special embodiment of the invention to provide a push-pull recording system using glow lamps which act as their own half-wave rectifiers. This may be accomplished by using two three-electrode glow lamps with their recording electrodes biased just below the extinction point and the third electrode biased to maintain a pilot glow. Thus the use of separate rectifying units is eliminated.

In any type of variable density sound recording, it is usually desirable to operate entirely on the straight line portion of the characteristic curve of the photographic emulsion, or at least to avoid the extreme lower end of the toe of this curve. One method of obviating any difficulties in this connection is to expose uniformly (flash) the sound tracks beyond a desired minimum value so that all light variations due to sound modulations act in addition to this flash exposure and thus on a useful portion of the characteristic

curve. As an added feature of the present invention when using either two-electrode or three-electrode glow lamps, this flash exposure can be provided by the pilot glow. This is accomplished by adjusting the biasing potential which maintains the pilot glow to a value which produces sufficient intensity in this glow to furnish the desired uniform flash exposure.

Other objects and advantages will be apparent 10 from the following description of detailed embodiments of the invention when read in connection with the accompanying drawings in which:

Fig. 1 shows the invention applied to ribbon type light valves.

Fig. 2 shows a section of a positive sound track resulting from a recording of the type illustrated in Fig. 1.

Fig. 3 shows a system similar to that used in Fig. 1 for recording variable density sound tracks.

Fig. 3A shows graphically the density variations of the sound track shown in Fig. 3.

Fig. 4 and Fig. 5 illustrates directly how the invention may be applied to two-electrode glow lamps.

Fig. 6 illustrates how the invention may be combined with push-pull amplification.

Fig. 7 illustrates the invention using three-electrode glow lamps.

Fig. 7A illustrates in a simple manner the principle of the arrangement shown in Fig. 7.

In Fig. 1 an input signal from a microphone 40 and its accompanying amplifying circuit 41 is introduced through a transformer having a primary 42 and a secondary 43. Two ribbon type light valves 46 and 47 are connected across this secondary 43, or may be connected across a portion of it or even have separate secondaries as shown in Fig. 3. A half-wave rectifier 44 is included in series with the valve 46 and a half-wave rectifier 45 is correspondingly included in the circuit of the valve 47. These rectifiers 44 and 45 are connected to have opposite directions of action as illustrated so that the valve 46 operates only on the positive half of each cycle and the valve 47 operates only on the negative half, or vice versa.

An optical system including a lamp 48, lenses 49, 50 and 51, and a diaphragm 52, projects an image of the aperture between the ribbons of each light valve to a sensitive film 53 on which the pictures may be recorded in areas 54 and 55 and the sound track is recorded in two portions 56 L and R. It will be noted that variations in width in either half of the track are contemporary with a region of uniform width in the other half.

In Fig. 2, the positive film 53 carrying pictures 54 and a positive sound track 56 corresponding with the sound track 24 of Fig. 1, demonstrates quite clearly that the light transmission of the positive sound track tends toward zero for low intensity signals. This produces the desired noiseless effect.

In Fig. 3 the light valves 46 and 47 are shown connected together for convenience in manufacture and hence must receive their signal from separate secondaries 57 and 58. In this particular arrangement the optical system includes separate masks 59 and 60 and a bi-prism 61 which is used to bring the two tracks to adjacent positions on the film. Any suitable optical system such as that shown may be used to produce a variable density push-pull sound track 62 on the film 53. The density variations in this track are shown in Fig. 3A. It will be noted that in this case also

the variations in light transmission in one track are accompanied by constancy of light transmission in the other track. As in the previous case this constant density is low in the negative and hence high in the positive giving noiseless recording.

In Fig. 4 the invention is applied in a simple manner to glow lamps 63 and 64, each of which is biased just above the extinction point by a source of potential 61 through suitable resistances. For lamp 63 these resistances are 66 and 68; for lamp 64, the resistances are 67 and 69. The input signal from the secondary 13 through the rectifiers 14 and 14', and the resistance 34 tends on one half of each cycle to increase the current flowing through the lamp 63 since the direction of rectification is the same as the direction of biasing for this lamp. Thus on one half of the cycle the lamp 63 receives current through the rectifiers 14 and 14' as well as from the source of potential 61, whereas the lamp 64 is unable to receive any signal current due to the rectifiers 15 and 15'. In this connection it should be noted that the source of potential 61 must be of a low resistance type so that the output flowing through the rectifiers 14 and 14' is unable to cause any change of potential across the glow lamp 64. If the rectifiers 15 and 15' are removed from the circuit and the source of potential 61 is connected to a center tap on the secondary 13 as shown by the broken line 13', a similar result would be obtained, but the response of the glow lamps would not exactly follow the half wave rectification of the input signal. In this case for zero input signal, the lamp 63 would receive current from the source of potential 61 through the resistance 66 and also through the upper half 26 of the secondary. During the positive half of an input signal this biasing current would be increased as discussed above, but on the negative half of the input this biasing current would not remain exactly constant but the portion flowing through 26 would be reduced—probably to zero. However the case illustrated using four rectifiers avoids this difficulty completely.

A somewhat more flexible arrangement for applying the invention to glow lamps is shown in Fig. 5 wherein resistances 34 and 35 are arranged in a bridge circuit with resistances 40 and 41. These resistances are adjusted to give the desired biasing potential from the source 61 across the lamps 63 and 64 to maintain them just above the extinction point. Furthermore, the ratio of the resistances 34 to 40, 35 to 41 and 43 to 42 are such that the points 44, 45 and 46 are at the same potential for zero signal input. The resistances 43 and 42 may be omitted if the point 46 is connected to a tap on the source of potential 61; the tap being adjusted to hold this point 46 at the potential of 44 and 45. The operation of this circuit is similar to that described in connection with Fig. 4. However the extra rectifiers 14' and 15' are unnecessary since there is zero current through the secondaries 26 and 37 for zero input signal, whereas the omission of 14' and 15' in Fig. 4 introduced a disturbing factor as discussed.

According to a very preferable embodiment of the invention as shown in Fig. 6 the rectifiers 14 and 15 may be replaced by electron discharge devices shown as triodes 48 and 49. The input circuits of these triodes are biased by a source of potential 47 so that there is zero output for zero input only. In the particular arrangement shown the glow lamp biasing potential 61 also acts as the plate supply for each of the triodes. To per-

mit convenient adjustment of the resistances in the circuit of the triodes 48 and 49 the lamps 32 and 33 are shunted by variable resistances 50 and 51 respectively.

5 The arrangement shown in Fig. 7 using three-electrode glow lamps and eliminating the use of any other type of half-wave rectifier is most easily explained by reference to Fig. 7A. A three-electrode glow lamp 52 is arranged with its 10 recording electrodes 54 and 56 across a secondary 26 of the input circuit. A resistance 34 is in series with these recording electrodes for added stability. A source of potential 66 and a resistance 64 are used to bias these recording electrodes just below the extinction point. The third electrode 58 of the glow lamp 52 is biased by a 15 source of potential 68 and through a resistance 60 to maintain in the lamp a glow between this pilot electrode and one of the recording electrodes, 20—in the case shown, electrode 56.

In the half of each cycle of the input signal which through the secondary 26 causes a potential across the electrodes 54 and 56 in the same direction as that caused by the biasing potential 25 66, a discharge between the two recording electrodes will occur since the presence of a pilot glow insures that the ignition and extinction points for the recording electrodes are the same. In the other half of the cycle the output of the 30 secondary 26 is in the opposite direction to the biasing potential 66 and hence tends to reduce the potential across the recording electrodes 54 and 56. Since the potential 66 is just at the extinction point, the glow between these two 35 electrodes goes out.

The other three electrode lamp 53 is biased to operate on the opposite half of each cycle. Since the purpose of the pilot electrode 58 is merely to maintain a pilot glow, it is immaterial whether 40 the potential of this electrode is positive or negative with respect to the electrode 56, provided that the difference in potential is sufficient to maintain the glow. In the three-electrode glow lamps commercially available, the electrodes 54 and 58 appear to be similar and the electrode 56 is of the crater type.

In the simplified arrangement shown in Fig. 7 the four sources of potential 66, 67, 68, and 69 are replaced by one source of potential 62. The 50 variable resistance 34 in addition to adding stability also provides the adjustment obtained by resistance 64 in Fig. 7A. The arrangement shown in Fig. 7A is not intended to be a practical one but is shown merely as an aid in discussing 55 the very useful embodiment shown in Fig. 7.

As pointed out previously the pilot glow in either the two-electrode or three-electrode flashing lamps may be adjusted to have sufficient intensity to give a uniform flash exposure of any 60 desired intensity to the film.

The advantages of the arrangements shown in Figs. 6 and 7 over any of the previous ones described are quite apparent and illustrate why 65 these arrangements are the preferable ones. A direct combination of the specific embodiments of the two figures is also quite useful but is not described here since in general it is unnecessary to use any additional rectifiers with the three-electrode glow lamps.

70 Having thus described our invention and two particularly preferable embodiments of it, we wish to point out that it is not limited to the specific arrangements shown but is of the scope 75 of the appended claims.

What we claim and wish to protect by Letters Patent of the United States is:

1. The method of operating light valves for Class B push-pull sound recording which comprises receiving an electric signal corresponding to the sound to be recorded, half-wave rectifying in the positive direction a portion of the signal, modulating a light valve in accordance with this half-wave rectification, half-wave rectifying in the negative direction another portion 10 of the signal and modulating another light valve in accordance with this latter half-wave rectification.

2. An electric circuit for push-pull sound recording comprising an input circuit for introducing the signal to be recorded, two light modulating devices, a circuit for each device including the device and means connecting it across a portion of the input circuit, an electrical half-wave rectifying means in each device circuit 20 for controlling the light modulating devices according to a half-wave rectification of the signal, the two rectifying means having opposite directions of action.

3. An electric circuit for noiseless sound recording comprising an input circuit carrying a full wave signal to be recorded, two light modulating devices adapted for push-pull recording, means connecting said input circuit to each of the light modulating devices and a half-wave 30 rectifier in series with each of the two connecting means for controlling the light modulating devices according to a half-wave rectification of the signal, the two rectifiers being oppositely coupled in their respective circuits. 35

4. An electro-optical system for push-pull variable density sound-on-film recording comprising an input circuit for introducing the signal to be recorded, two light modulating devices, two light beams the intensities of which are modulated thereby, optical means projecting said modulated beams to different tracks on the film, and electrical means including half-wave rectifiers connecting each of the light modulating devices to the input circuit for controlling these devices 40 according to a half-wave rectification of the signal, the two rectifiers being opposed and acting alternately.

5. An electric circuit for push-pull sound recording including an input circuit carrying the 50 signal to be recorded, two glow lamps connected to the input circuit, said glow lamps having a plurality of electrodes, two electrodes in each lamp being biased just above the extinction point, the biasing of the two lamps being in opposite 55 directions and two electrodes in each lamp forming a complete series circuit with a portion of the input circuit, said series circuit including means passing uni-directional current only, said last mentioned means for one lamp being in the opposite direction from that for the other lamp.

6. An electric circuit for push-pull sound recording including a signal input circuit, two flashing lamps, means including half-wave rectifying means connecting each lamp across a portion 65 of the input circuit, and a source of potential biasing said lamps just above the extinction point and supplying current which maintains a glow in each lamp, said biasing and rectifying means being for each lamp in the same direction 70 and for either lamp in a direction opposite to that for the other lamp.

7. An electric circuit for push-pull sound recording including an input circuit, two electron discharge devices connected in push-pull across 75

the input circuit, a glow lamp across the output of each of the electron discharge devices, and means biasing each lamp just above the extinction point in the same direction as the output of the corresponding electron discharge device which is biased giving zero output for zero input only.

8. In push-pull sound recording, an input circuit carrying a full wave corresponding to the sound to be recorded, two glow lamps, means for operating one lamp on the positive half of the wave, means for preventing the operation of this lamp on the negative half of the wave, means for operating the other lamp on the negative half, means for preventing the operation of this other lamp on the positive half of the wave, and a source of potential maintaining a glow in each lamp.

9. An electric circuit for push-pull sound recording comprising an input circuit, two three-electrode glow lamps, means connecting a pair

of electrodes of one lamp across a portion of the input circuit, means connecting a pair of electrodes of the other lamp across a portion of the input circuit, a source of potential biasing said pairs oppositely just below the extinction point and means including the third electrode maintaining a glow in each lamp.

10. In push-pull sound-on-film recording, two glow lamps operating respectively on positive and negative half-wave rectifications of the sound to be recorded and means maintaining a pilot glow in each lamp having a predetermined intensity sufficient uniformly to expose the film beyond the non-useful portion of the toe of its characteristic curve whereby all additional exposure caused by increased glow due to the sound input will be recorded on a useful portion of said characteristic curve.

JOHN H. MCLEOD. 20
